UNITED STATES PATENT OFFICE.

SIMON STEINAM AND ABBOTT L. SEELIGMAN, OF NEW YORK, N. Y.

KNITTED OR CARDIGAN JACKET.

SPECIFICATION forming part of Letters Patent No. 317,682, dated May 12, 1885.

Application filed January 26, 1885. (No model.)

To all whom it may concern:

Be it known that we, SIMON STEINAM and ABBOTT L. SEELIGMAN, both of the city and county of New York, in the State of New York, have invented a new and useful Improvement in Knitted or Cardigan Jackets, of which the following is a specification.

Cardigan jackets are made from a circular fabric woven or knitted on a circular machine, and to give the upper part of the jacket the proper shape the fabric is cut and the cut edges are brought together and enchain, or "chained" together, as it is termed, on a suitable machine, to form the shoulder-seams. The chaining of the shoulder-seams is done by a single thread or yarn, and these seams become the weakest part of the jacket, and are very apt to tear out, especially when the jacket is put on by a stout person.

20 The object of our invention is to strengthen or re-enforce these seams by means which are in keeping with the jacket, and which do not mar its appearance.

25 The invention consists in a Cardigan jacket having the chained shoulder-seams re-enforced by a strip or piece of knit webbing secured to them, the said webbing being preferably continuous between the shoulder-seams and around the neck-seams.

30 The accompanying drawing represents a jacket embodying our invention.

A designates the body, B the sleeves, and C the neckband of a Cardigan jacket. This jacket consists of a knitted fabric, as represented at a, and in the operation of making the jacket after the circular fabric, has been knitted the fabric is cut, and the edges where cut are brought together and enchain, or chained together, by a well-known machine, 35 thereby forming shoulder-seams b. But a single thread or yarn is usually employed to chain the seams, and hence these seams are

the weakest points in the jacket. Frequently the jacket will break out or tear at these seams before it is much worn, especially if the wearer 45 be stout. To obviate this difficulty we re-enforce these seams by a webbing, D, of knitted material similar and corresponding in appearance and color to the fabric of which the jacket is made. This webbing is laid on the seams 50 b, and is secured to the jacket by rows of stitching. In the drawing we have represented the webbing D as continuous between the shoulder-seams b and around the seam at the back of the neck, where the neckband is 55 secured to the body of the jacket, but the right-hand end of the webbing is represented as unattached to more clearly show its form. The webbing is here shown as on the exterior 60 of the jacket, and as it is of knitted fabric like the jacket it does not detract from the appearance thereof. The covering and re-enforcing of the shoulder-seams by the webbing of knitted fabric renders this part of the jacket as strong 65 or stronger than the remainder, and is therefore very desirable.

What we claim as our invention, and desire to secure by Letters Patent, is—

1. A knitted or Cardigan jacket, having the chained or enchain shoulder-seams b, and a 70 knitted webbing, D, applied to and re-enforcing the said seams, substantially as herein described.

2. A knitted or Cardigan jacket, having the chained or enchain shoulder-seams b, and a 75 knitted webbing, D, applied to and re-enforcing said seams, and made continuous between said seams and around the neck, substantially as herein described.

SIMON STEINAM.

ABBOTT L. SEELIGMAN.
